SELF-FILLING FOUNTAIN PEN

Erskine Long, Pittsburgh, Pa.

Application September 11, 1934, Serial No. 743,520
Renewed August 20, 1936

14 Claims. (Cl. 120—47)

This invention relates to a fountain pen and more particularly an automatic self-filling fountain pen.

One object of the present invention is to provide a fountain pen having an exceedingly large ink reservoir which may be readily filled by simply turning the pen from an upright position, in which the point extends upwardly, to a writing position and inserting the point in a suitable ink container.

Another object of the present invention is to provide a fountain pen having means for expanding the air in the ink reservoir when the pen is turned from an upright position to the writing position for the purpose of creating a partial vacuum whereby ink will be drawn into said reservoir on the insertion of the point into a suitable ink container.

A further object of this invention is to provide a fountain pen which is simple in construction, positive in operation, easy to manufacture and in which the ink is positively retained within the reservoir.

These and other objects which will be herein-after made apparent to those skilled in this particular art, are accomplished by means of this invention, one embodiment of which is illustrated in the accompanying drawing, wherein:

Figure 1 is a view in longitudinal section of a fountain pen made in accordance with my invention;

Fig. 2 is a section taken on line II—II of Fig. 1; Fig. 3 is a section taken on line III—III of Fig. 1, and

Fig. 4 is a view in longitudinal section illustrating a modification of my invention.

Referring to the drawing in detail, my improved pen comprises a barrel or shell 5 of the usual construction, serving as an ink reservoir and having its upper end closed by a cap 6 and a sleeve 7 threaded into its lower end which supports the usual point 8 and plug 9. The plug 9 is provided with the usual groove 10 underneath the point 8 which leads to the ink reservoir and serves as an ink inlet passage for filling up the pen and as an outlet passage when the pen is in use.

In order that the pen may be readily and automatically filled with ink, a tubular member or barrel 11 having a closed lower end is mounted within the shell 5 with its closed end abutting against the upper end of the plug 9. This tubular member 11 which is of substantially smaller diameter than the diameter of the shell 5 so that, when positioned on the plug 9, it will not cover the upper end of the passageway 10, is held in spaced relation to the shell by means of spacer spokes 12 having their ends cemented to the outer surface of the tubular member 11 and the inner surface of the shell 5. The upper end of

the tubular member 11 is closed by a loose flexible diaphragm 13 made of rubber or any other suitable material which is secured to the outer surface of the tubular member by means of a ring 14 which clamps the edges of the diaphragm in a groove 15 formed in the outer wall of the member 11. The diaphragm 13 has a weight 16 secured thereto which is slidably contained in the tubular member 11 and is movable into and out of said member to actuate said diaphragm. 10 The lower end of the tubular member 11 is connected to atmosphere by a sleeve 19 which has its ends secured in openings in the wall of the shell 5 and tubular member 11, respectively. From this arrangement, it is apparent that the 15 member 11 divides the interior of the shell 5 into an ink reservoir or chamber 20 and an air chamber 21 which are separated by the flexible diaphragm 13.

To fill the pen, it is first turned to a position 20 with the point 8 extending upwardly whereby the weight member 16 in the tubular member 11 moves toward the upper end of the shell 7 so flexing the diaphragm that the weight and diaphragm enter the upper end of the chamber 20, 25 materially reducing the volume thereof and forcing the excess air through the groove 10. The pen 5 is then quickly inverted and the point 8 inserted into a suitable supply of ink such as a bottle or other container, to such a depth that 30 the lower end of the passageway 10 is submerged therein. In this position, the weight 16 falls by gravity to its lower position, illustrated in the drawing and exhausts the air in the chamber 21 through the duct in the sleeve 19. Since the 35 opening of the passageway 10 is immersed in a liquid during this movement of the weight 16, it is apparent that the volume of the chamber 20 is increased and the air remaining therein will 40 be expanded and create a partial vacuum which causes ink to flow through the passageway 10 into the chamber or ink reservoir 20. By repeating this operation the pen may be filled to any desired extent.

If desired, the weight 16 may be releasably locked in the tube 11 to prevent its movement back and forth therein during the normal use of the pen. To lock the weight 16 in the position illustrated in the drawing, that is in its lowermost position, a hollow pin 22 may be slidably mounted in the sleeve 19 which, when in its innermost position, enters a groove 23 formed in the periphery of the weight 16. With this construction, when the pen is to be filled, the pin is 55 first retracted and then the pen is so turned that the weight 16 moves into the chamber 20. After the filling operation as above described, and while the pen is held in position for writing, the pin 22 is moved inwardly so that the end thereof 60

re-enters the groove 23 and locks the weight against movement.

In Fig. 4, a modification of my invention is illustrated in which a piston plunger 30 is slidably mounted in the tubular member 11' mounted within the shell 5'. This piston 30 is preferably made from or filled with some relatively heavy material so that, as the pen is turned about its horizontal axis, it will fall by gravity and force the air out of the chamber 20' through the passageway 10' when moving in one direction, and force the air in the chamber 21' through the sleeve 19' when moving in the opposite direction and thus create a partial vacuum in the chamber 20' which will cause ink to flow into the reservoir.

The piston 30 is provided with an extension 31 which is of sufficient length to engage the cap 6' and prevent the piston 30 from passing beyond the upper end of the tubular member 11' when the pen is held with the point in raised position.

From the foregoing description of my invention, it is apparent that I have provided a fountain pen which is simple in construction and is readily filled with ink by simply turning the pen from one position to another to create a partial vacuum in the ink reservoir and then inserting the point in a suitable supply of ink.

While I have described the member 11 and the shell 5 as made separately and then joined together, it is understood that the two parts may be readily cast integrally and that other changes, modifications, omissions, and additions may be made therein without departing from the spirit of my invention or the scope of the appended claims.

What I claim as new and desire to secure by Letters Patent is:

1. A fountain pen comprising an outer barrel, an inner barrel spaced from said outer barrel and in communication with atmosphere, said barrels forming an ink reservoir therebetween, a pen point positioned in the end of said outer barrel and communicating with said reservoir, means for closing the upper end of said inner barrel, and means for flexing said closure means when said pen is turned about its horizontal axis to expand the air in said ink reservoir.

2. A fountain pen comprising a shell, a grooved plug closing the end of said shell, an inner tubular member within said shell having one end thereof connected to atmosphere, a diaphragm closing the opposite end of said member, and means slidably within said member for actuating said diaphragm to vary the volume of the chamber between said member and said shell.

3. A fountain pen comprising an outer barrel, an inner barrel spaced from said outer barrel and forming an ink reservoir therebetween, a point assembly carried by said outer barrel and communicating with said reservoir, and means actuated by turning the pen about its horizontal axis for creating a partial vacuum in said reservoir.

4. A fountain pen comprising a shell having a closed end and an open end, a tubular member within said shell and having a passage leading to the exterior surface of the shell, a grooved point assembly closing the open end of said shell and having the groove opening into the space between said shell and member, and a weighted diaphragm closing the end of said member.

5. An automatic filling fountain pen comprising an outer hollow member having a closed upper end, a hollow member in constant communication with atmosphere mounted within said outer member and forming a chamber therebetween, a

point assembly closing the lower end of said outer member having a passageway leading to said chamber, a flexible diaphragm closing the upper end of said inner member, and means associated with said diaphragm for flexing the diaphragm on the turning of the pen about its horizontal axis.

6. A fountain pen having an ink chamber, and air chamber, a flexible member separating said chambers and means for flexing said member to vary the volume of said chambers when the pen is turned about its horizontal axis.

7. A fountain pen having an ink chamber, an air chamber, and means for creating a partial vacuum within said ink chamber including a diaphragm separating said chambers and gravity actuated means for flexing said diaphragm.

8. A fountain pen having a barrel, means for dividing the interior of said barrel into an ink chamber and an air chamber, a flexible member separating said chambers, and a weight attached to said flexible member for flexing the same.

9. A fountain pen having an ink chamber, an air chamber, and means for reducing the pressure in said ink chamber comprising a flexible member separating said chambers and means attached to said flexible member and contained in said air chamber for varying the volume of the ink chamber on the turning of said pen.

10. A fountain pen having a shell, a grooved point assembly closing the lower end of said shell, a hollow member disposed within said shell and connected to atmosphere, said hollow member being spaced from said shell to form an ink reservoir therebetween, and means associated with said hollow member and operable when said pen is turned from a position with the point upright to a position with the point extending downwardly for exhausting the air from said hollow member and increasing the volume of said ink reservoir.

11. A fountain pen of the character described comprising a barrel having a closed end, a tubular member within said barrel and dividing the interior thereof into an ink space and an air space, a pen point mounted on one end of said barrel and communicating with said ink space, and a plunger slidably mounted in the tubular member to vary the capacity of said air space.

12. A fountain pen of the character described comprising a barrel having one end thereof closed, a tubular member within said barrel for dividing the interior thereof into an ink space and an air space, a pen point mounted in the open end of said barrel and communicating with said ink space, a plunger slidably mounted in said tubular member, and means for releasably locking said plunger in one position in said tubular member.

13. A fountain pen of the character described comprising a barrel means for dividing the interior of said barrel into an ink space and an air space, and a weighted member movable in the air space for progressively varying the volume of said respective spaces.

14. A fountain pen comprising a barrel, means for dividing the interior of the barrel into an ink chamber and an air chamber, a point assembly carried by said barrel and communicating with the ink chamber, and movable means for separating said chambers and operable when said pen is turned from a position with the point upright to a position with the point extending downwardly to decrease the volume of the air chamber and increase the volume of the ink chamber to thereby expand the air contained therein.

ERSKINE LONG.
